Des. 227,813
Patented July 17, 1973

227,813

SELF-PROPELLED CART FOR INVALIDS

Antony Charles Robert Armstrong Jones, Kensington
Palace, London, England

Filed May 4, 1972, Ser. No. 250,484

Claims priority, application Great Britain Nov. 10, 1971

Term of patent 14 years

Int. Cl. D12—12

U.S. Cl. D83—1 E

Fig.1.

Fig.2.

Fig. 3.

FIG. 1 is a front perspective view of a self-propelled cart for invalids showing my new design;

FIG. 2 is a rear perspective view; and

FIG. 3 is a top plan view thereof.

I claim:

The ornamental design for a self-propelled cart for invalids, as shown and described.
